Patented July 7, 1914.

UNITED STATES PATENT OFFICE.

BIRGE W. DAVENPORT, OF MINNEAPOLIS, MINNESOTA.

STARTER FOR INTERNAL-COMBUSTION ENGINES.

1,102,479.

Specification of Letters Patent.

Patented July 7, 1914.

Application filed February 16, 1912. Serial No. 678,060.

To all whom it may concern:

Be it known that I, BIRGE W. DAVENPORT, a citizen of the United States, residing at Minneapolis, in the county of Hennepin and State of Minnesota, have invented certain new and useful Improvements in Starters for Internal-Combustion Engines; and I do hereby declare the following to be a full, clear, and exact description of the invention, such as will enable others skilled in the art to which it appertains to make and use the same.

My invention relates to starters for internal combustion engines.

It has for its object to provide an improved device, which is simple in construction, reliable and durable in operation and which dispenses with the necessity of cranking the engine by hand.

Other objects will become apparent from the following description.

The invention consists of pawl and ratchet mechanism mounted on the engine shaft and actuated by compressed air or other suitable means which is transmitted to said pawl and ratchet mechanism by a flexible connection extending around the periphery of a wheel or disk loosely mounted on the shaft. The ratchet wheel is keyed or otherwise made fast to the shaft. The pawl is carried by a loose disk which is separate from the wheel to which the flexible connection is attached. Said pawl normally rests out of engagement with the ratchet wheel but is thrown into contact therewith, when the starter is operated, by a lug on the wheel carrying the flexible connection. Suitable resilient means are provided for returning the starter to its initial position after each operation. The pawl carrying disk has a stop projecting from its surface into the path of the lug which throws the pawl, said stop being adapted to be engaged by said lug for returning the pawl-carrying-disk to its initial position with the other parts of the starter.

The invention also consists in the features of construction and combinations of parts, hereinafter described, illustrated in the accompanying drawings, and specified in the appended claims.

In the accompanying drawings:—Figure 1 is a side elevation of my improved starter, parts being broken away. Fig. 2 is a similar view showing the position of the parts at the end of the operation of the starter,

and Fig. 3 is a sectional view taken through the starter disks longitudinally of the shaft.

Referring more particularly to the drawing, 1 designates a compressed air cylinder in which is mounted a piston 2 and to which compressed air is admitted from any suitable source, not shown, by means of a three-way valve or cock 3. The piston rod 4 projects through the other end of the cylinder 1 and to it is connected one end of a sprocket chain 5, which is passed around a sprocket wheel or disk 6, with its other extremity secured thereto. The sprocket wheel 6 is provided with a collar 17, said wheel 6 being loosely mounted upon the engine shaft 9. A collar or sleeve 7 is mounted on said shaft 9, said collar 7 having a disk 8 integral therewith and positioned parallel to said sprocket wheel. This disk 8 is provided at or near its periphery with a laterally projecting flange or rim 10 extending in an opposite direction to that of the collar or sleeve 7, thereby forming a recess or pocket between the disk 8 and the sprocket wheel 6, for the purpose of housing the ratchet 12. A slot 13 is formed in the flange or rim 10 in which the pawl 14 is pivoted. Said slot and pawl are arranged at the bottom of the disk below the ratchet when the starter is in its normal position before operation. When in this position the pawl remains out of engagement with the ratchet by means of gravity. The tail of the pawl projects outwardly through its slot into the path of the lug 15 rigidly secured to the side of the sprocket wheel. In the normal position of the device this lug lies adjacent to, but out of contact with the tail of the pawl. The pawl-carrying-disk is further provided with a stop 16 also extending into the path of the lug 15 and normally arranged near to the other end thereof. To the collar 17 of the sprocket wheel 6, there is attached one end of a flexible wire cable or chain 18, the other end of which is secured to a helical spring 19 fastened to a fixture, such as the cylinder 1. The cable or chain 18 winds upon the collar 17 in the opposite direction from that in which the sprocket chain 18 is wound upon the sprocket wheel. The result is that, when the starter is operated, the spring will be extended, so that it will return said starter to normal position after the pressure in the cylinder has been removed.

The operation of my invention is very

simple. When compressed air is admitted to the cylinder behind the piston by means of the valve or cock 3, the piston rod is forced outwardly, resulting in the rotation 5 of the sprocket wheel from the position shown in Fig. 1 to the position shown in Fig. 2. Soon after the sprocket wheel begins to turn, its lug 15 will engage the tail of the pawl and raise the latter into contact 10 with the ratchet so that further rotation of the sprocket wheel will cause the engine shaft to be rotated and the engine started thereby. When the piston has reached the end of its outward stroke and the engine 15 has been started, the pressure behind the piston in the cylinder is removed by suitably adjusting the three-way valve or cock 3. As soon as this pressure is removed the spring operates to return the sprocket wheel 20 and piston to normal positions. As already explained, the lug on the sprocket wheel engages the stop on the pawl-carrying-disk and returns the latter to the normal position with said sprocket wheel.

25 I claim:-

1. In a starter for internal combustion engines, the combination, with a ratchet fast on the engine shaft, of a disk mounted loosely on said shaft, a pawl pivoted on said 30 disk below the ratchet, another loose disk having a lug adapted to engage said pawl and throw it into contact with the ratchet when said last-mentioned disk is rotated, and means to rotate said disk for the purpose 35 specified.

2. In a starter for internal combustion engines, the combination, with a ratchet fast on the engine shaft, a disk loosely mounted on said shaft, a pawl pivoted on said disk 40 below the ratchet and normally lying out of engagement therewith; another loose disk carrying a lug adapted to throw the pawl into contact with the ratchet when said last-mentioned disk is rotated, a stop on the 45 pawl-carrying-disk at the other side of said lug, means to rotate the lug-carrying-disk, and means to automatically return said disks to normal position after each operation.

3. In a starter for internal combustion 50 engines, the combination, with a ratchet fast on the engine shaft, of a disk loosely mounted on said shaft and having a laterally extending flange on its periphery housing said ratchet, said flange having a slot therein, a 55 pawl pivoted in said slot and normally arranged below the ratchet, the tail of said pawl projecting outwardly through said slot, another loose disk carrying a lug adapted to engage the tail of the pawl for throwing said pawl into contact with the ratchet

when said last mentioned disk is rotated, and means to rotate said disk for the purpose specified.

4. In a starter for internal combustion engines, the combination, with a ratchet fast 65 on the engine shaft, of a disk loosely mounted on said shaft and having a laterally extending flange on its periphery, said flange having a slot therein, a pawl mounted in said slot below the ratchet and normally lying out of engagement therewith, the tail of the pawl extending outwardly through said slot, another loose disk having a lug adapted to engage the tail of the pawl for throwing said pawl into contact with the ratchet 75 when said last mentioned disk is rotated, a stop on said pawl-carrying-disk at the other side of said lug, means to rotate said lug-carrying-disk, and means to automatically return said disk to the normal position after 80 each operation.

5. In a starter for internal combustion engines, the combination, with a ratchet fast on the engine shaft, of a disk loosely mounted 85 on the shaft, a pawl pivoted on said disk and normally lying out of engagement therewith, another loose disk having a projecting collar, a lug on said last mentioned disk adapted to throw the pawl into contact with the ratchet when said disk is rotated, a stop 90 on the pawl-carrying-disk at the other side of said lug, means to rotate said lug-carrying-disk, and a spring having one end secured to a fixture and the other end connected to the collar on said last mentioned 95 disk, whereby both disks are automatically returned to normal position after each operation.

6. In a starter for internal combustion engines, the combination, with a ratchet fast 100 on the engine shaft, a disk loosely mounted on said shaft, a pawl pivoted on said disk and normally lying out of engagement with said ratchet, another loose disk having means for throwing the pawl into contact 105 with the ratchet when said last mentioned disk is rotated, a cylinder, a piston mounted in said cylinder, and having a piston rod extending through the end of the same, flexible connection between said piston rod 110 and the last mentioned disk, which is passed around the latter, and means for reciprocating the piston.

In testimony whereof, I affix my signature, in presence of two witnesses.

BIRGE W. DAVENPORT.
